(57) **CLAIM**

The ornamental design for a mini exhaust hood, as shown and described.

DESCRIPTION

FIG. 1 is a perspective view of the mini exhaust hood, showing the new design;

FIG. 2 is a front elevation of the new design;

FIG. 3 is a rear elevation of the new design;

FIG. 4 is a left side elevation of the new design;

FIG. 5 is a right side elevation of the new design;

FIG. 6 is a plan view of the new design; and,

FIG. 7 is a bottom projection of the new design.

The broken lines are included for the purpose of illustrating unclaimed portions of the mini exhaust hood and form no part of the claimed design.
